LADY'S SLIPPER OR SIMILAR ARTICLE

John A. Lacek, Dolgeville, N.Y., assignor to Daniel Green Company, Dolgeville, N.Y., a corporation of Massachusetts

Filed Nov. 27, 1959, Ser. No. 58,468

Term of patent 14 years

(Cl. D7—7)

Fig. 1 is a perspective view of a lady's slipper or similar article showing my new design; and

Fig. 2 is a side view of the slipper as seen from the side opposite that shown in Fig. 1.

I claim:

The ornamental design for a lady's slipper or similar article, substantially as shown.
